UNITED STATES PATENT OFFICE.

OTIS A. MYGATT, OF NEW YORK, N. Y.

DESIGN FOR A GLASS SHADE OR REFLECTOR.

46,098.

Specification for Design.

Patented July 14, 1914.

Application filed June 5, 1908. Serial No. 437,002. Term of patent 14 years.

To all whom it may concern:

Be it known that I, OTIS A. MYGATT, a citizen of the United States, residing at New York, in the county of New York and State of New York, have invented a new, original, and ornamental Design for Glass Shades or Reflectors, of which the following is a specification, reference being had to the accompanying drawing, forming part thereof.

The drawing is a bottom perspective of a shade or reflector embodying my design.

My design consists in the provision upon the outer surface of a transparent glass shade or reflector of angular jewel-like protuberances and upon the inner surface substantially radially disposed prisms backing up the aforesaid protuberances.

More specifically considered, my design

consists of a glass shade or reflector having a skirt portion with angular jewel-like protuberances on the outer surface thereof and substantially radially disposed prisms on the inner surface thereof backing up the aforesaid protuberances.

I claim—

The ornamental design for a glass shade or reflector comprising a skirt portion having upon the outer surface thereof angular jewel-like protuberances and upon the inner surface thereof substantially radially disposed prisms backing up the aforesaid protuberances.

OTIS A. MYGATT.
